CLAIM

The ornamental design for a minitower computer, as shown and described.

DESCRIPTION

FIG. 1 is a top, front, and right-side perspective view of a minitower computer showing my new design;

FIG. 2 is a front elevational view thereof;

FIG. 3 is a left-side elevational view thereof;

FIG. 4 is a right-side elevational view thereof;

FIG. 5 is a top plan view thereof;

FIG. 6 is a bottom view thereof; and,

FIG. 7 is a rear elevational view thereof.

The broken line showing various ports and connectors in FIG. 7 is for illustrative purposes only and forms no part of the claimed design.
